UNITED STATES PATENT OFFICE.

LESTER H. SPARKS, OF LAKEWOOD, NEW JERSEY, ASSIGNOR OF FORTY-NINE ONE-HUNDREDTHS TO JENNIE L. MILLER, OF LAKEWOOD, NEW JERSEY.

TRANSMISSION-LOCK.

1,228,253.

Specification of Letters Patent. Patented May 29, 1917.

Application filed March 9, 1914, Serial No. 823,482. Renewed February 26, 1917. Serial No. 151,124.

To all whom it may concern:

Be it known that I, LESTER H. SPARKS, a citizen of the United States, residing at Lakewood, in the county of Ocean, State 5 of New Jersey, have invented certain new and useful Improvements in Transmission Locks; and I do hereby declare the following to be a full, clear, and exact description of the invention, such as will enable others 10 skilled in the art to which it appertains to make and use the same.

This invention relates to transmission locks and has special reference to a transmission lock adapted to lock the two operating 15 rods of a two rod operating transmission in immovable relation with respect to each other.

The principal object of the invention is to provide an improved lock of this character 20 which is used in connection with a timer of the type described in my co-pending application No. 764,632, filed April 30th, 1913.

Another object of the invention is to provide a novel means whereby, at the proper 25 time, any manipulation of the transmission lock causes the same to be securely locked even though the timer mechanism is operated previously.

A third object of the invention is to provide means for insuring the full throw of the locking element.

With the above and other objects in view the invention consists in general of certain novel details of construction and combination 35 of parts hereinafter fully described, illustrated in the accompanying drawings, and specifically claimed.

In the accompanying drawings, like characters of reference indicate like parts in the 40 several views, and:

Figure 1 is a view showing the general position of the device with relation to a transmission.

Fig. 2 is an end view of the apparatus with 45 the cover thrown back, the electrical connection to the timer being diagrammatically shown.

Fig. 3 is a plan view of the device with the cover thrown back.

Fig. 4 is a section on the line 4—4 of 50 Fig. 3.

Fig. 5 is a detached view showing a portion of one of the rods.

In carrying out the objects of the invention there is provided a casing 10 which 55 is normally closed by a cover 11. At 12 is indicated the casing for the transmission gearing, the latter being operated by means of the rods 13 and 14. The rod 13, which is normally continuous, is cut in two and 60 threaded into suitable openings 15 at each end of the casing so that the latter is held immovable on said rod. In like manner the rod 14 is cut in two and the cut ends are screwed into a bar 16 provided with a rib 65 17 having a step notch 17' formed therein to receive the locking member. This bar and rib are received in a key hole opening 18 extending through the casing.

It is to be observed that the rear part of 70 the casing is formed of a solid block as at 20 and is provided with a lubricating opening 19 so that oil may be supplied to the bar 16. This block 20 is slotted as at 21 and pivoted to swing in this slotted portion 75 22. Mounted on the base of the device is a stop pin 23 which is adapted to be engaged by a stop pin 24 to limit outward swinging movement of the bar. Also mounted on this base are the magnets of 80 which there are two pairs indicated respectively at 25 and 26. Furthermore on this case is an insulating block 27 whereon is mounted a contact 28 which is connected through the magnets 25 to a binding post 85 29. On the block is a similar contact 30 connected through the magnets 26 to a binding post 31. There is also provided a third binding post 32 on said block and this binding post is connected by a wire 33 with a 90 contact arm or finger 34 which is carried by an insulating arm 35 on a shaft 36. Fixed on the shaft 36 are arms 37 which carry the armatures 38 and 39 which are adapted to be attracted by the magnet cores 41, the 95 latter being cut away as at 40 to permit full movement of said armatures while keeping them in the magnet field. Extending

through the shaft 36 is a pin 36' which works in a slot 36'' formed in a projection on the insulating arm 35 so that the contact finger 34 need not move to the full extent of 5 movement of the shaft 36.

At 42 is a battery which is connected by a wire 43 with the contact 32 by a wire 44 with the timer 45. This timer is connected by a wire 46 with the contact 29 and by a wire 47 with the contact 31. Moreover a testing circuit is employed which includes the wire 48, circuit closer 49 and bell 50, the circuit extending between the wires 43 and 47.

Depending from the armatures 39 is an arm 51 which carries at its lower end a pivot pin 52 movable in a slot 53 in a link 54 provided at its other end with a shorter slot 55. A pin 56 passes through the slot 20 55 and serves to connect the link 54 with the arm or bar 22. At the bottom of the casing is an ear 57 whereon is pivotally mounted an arm 58 which is connected at its upper end to the pin 52. Surrounding 25 the arm and normally urging the arm 51 to one extreme position or the other, is a coil spring 59.

In the operation of the device when the timer mechanism so operates as to throw the 30 wire 46 into connection with the wire 44 then the circuit will be established through the magnets 25. The result of this will be to draw down the parts to the position shown in full lines in Figs. 2 and 4. If 35 however the wire 47 be connected by the operation of the timer mechanism then the magnets 26 will be energized. This will cause the attraction of the left hand armature in Fig. 2 by the poles 41 of the left 40 hand magnet with the consequence that these will be drawn down. Thus the bar 22 will be swung to the position shown in dotted lines in Fig. 4 and will be forced to extreme position by the operation of the 45 spring 59, since as soon as the pin 52 passes to the right of the center line between the shaft 36 and the shaft 60, which forms the pivot of the arm 58 on ear 57, the tendency of the spring will be to constantly move the 50 link farther to the right. At the same time the contact 34 will move to the right and break the circuit thus throwing the battery out of circuit. If now the timer mechanism again operates to energize the right hand 55 magnet 25 then the same operation will take place with a tendency to throw the bar 22 into the notch 19. However, if the bar cannot be thrown into the notch by reason of this notch not being in exact position, then 60 the link 54 will only move to such position that the pin 52 is slightly to the left of the line connecting the shafts 36 and 60. Yet, when the notch does arrive at the correct 65 position the action of the spring 59 will complete the action of the magnetic means

and force the arm 22 fully inward thus locking the shafts 13 and 14 from relative movement.

There has thus been provided a simple and efficient device of the kind described 70 and of the character specified.

It is obvious that many minor changes may be made in the form and construction of this invention without departing from the material principles thereof. It is not 75 therefore desired to confine the invention to the exact form herein shown and described, but it is wished to include all such as come properly within the scope claimed.

Having thus described the invention, 80 what is claimed as new, is:

1. The combination with a lock casing, of a member slidable therethrough the said member having a notch therein, a lever pivotally supported in the said casing and 35 adapted to engage said notch, a plurality of electro-magnets, a link connecting the said lever and the armatures of said magnets, means to control the energizing of said magnets to move said links and resilient means for completing the movement of said links. 90

2. In combination with a lock casing, a member slidable therethrough and having a notch therein, a lever adapted to engage 95 said notch when the latter is in a predetermined position, a plurality of electro-magnets, a link connecting said lever and the armatures of said magnet, means to control the movement of said armatures to move 100 the lever toward the aforementioned slid-able member and resilient means for completing the movement of the said lever when the notch in the said slid-able member reaches a predetermined position. 105

3. The combination with a lock casing of a member slidable therethrough, the said member having a notch therein, means to engage said notch to lock the said slid-able member, means to move the said last men-tioned means, and means to complete the movement of the notch engaging means to move it into the notch in the said slid-able member when the said notch arrives in alinement therewith. 110

4. The combination with a lock casing; of a member slidable therethrough and pro-vided with a locking notch, a plurality of electro-magnets, an armature lever pivoted intermediate said magnets, a pair of armatu-tes on said lever arranged for selective at-traction by said magnets, a locking mem-ber mounted on said casing to engage said notch, an arm depending from said armature lever, a link connecting the locking member and arm, and means to move said arm to extreme positions after energization of a selected magnet. 125

5. The combination with a lock casing; of a member slidable therethrough and pro-130

vided with a locking notch, a plurality of electro-magnets, an armature lever pivoted intermediate said magnets, a pair of armatures on said lever arranged for selective attraction by said magnets, a locking member mounted on said casing to engage said notch, an arm depending from said armature lever, a link connecting the locking member and arm, means to move said arm 10 to extreme positions after energization of a

selected magnet, and means to break a circuit through the selected magnets when the armature lever has been rocked to a predetermined point.

In testimony whereof, I affix my signature, in the presence of two witnesses.
